UNITED STATES PATENT OFFICE.

LIONEL F. BARNES, OF ALDERSHOT, ENGLAND.

LOCK-SWITCH.

1,291,722.

Specification of Letters Patent. Patented Jan. 21, 1919.

Application filed July 27, 1915. Serial No. 42,229.

To all whom it may concern:

Be it known that I, LIONEL F. BARNES, a subject of the King of Great Britain, at present residing at Aldershot, in the county 5 of Hants, England, have invented certain new and useful Improvements in Lock-Switches, of which the following is a specification.

My invention relates to electric circuit 10 closers and more particularly to a circuit closer which is provided with means for preventing closing of the circuit by unauthorized persons, the device being particularly adapted for use in connection with the 15 ignition circuits of motor vehicles, motor boats, and the like.

The primary object of my invention is to provide a circuit closer of the class above mentioned which will normally maintain 20 an open circuit and which is only capable of closing when a key provided therefor is inserted.

Another object of my invention is to provide a circuit closer of the class above mentioned which is simple in construction, cheap to manufacture, strong and durable, and effective in operation.

With the above and other objects in view my invention resides preferably in the construction, combination, and arrangement of parts as hereinafter set forth in the specification and illustrated in the accompanying drawings, in which—

Figure 1 is an exterior view of the circuit closer embodying the improvements of 35 my invention.

Fig. 2 is a longitudinal sectional view of my improved circuit closer showing the operating mechanism in plan view.

Fig. 3 is a rear elevational view of the housing showing the operating mechanism in elevation.

Fig. 4 is a detail enlarged perspective view of the key member which I use in the present 45 form of my invention.

Fig. 5 is a detail enlarged view of one terminal of the circuit closer.

Similar reference characters indicate similar parts throughout the various views of 50 the drawings.

In the drawings wherein the preferred embodiment of my invention is illustrated, I have provided a housing 1 of any desired shape and formed of any preferred material, 55 such as hard rubber or the like. A base 2 is

associated with the housing 1 and is detachably connected thereto by means of fastening screws 3 or the like. As shown to advantage in Figs. 2 and 3, the housing 1 includes a curved front wall 4 and side walls 60 5 and 6.

The circuit closing mechanism of my invention includes a transversely arranged guide member 7 preferably formed of tubular material and having a longitudinal slot 65 8 formed therein, said slot terminating in an enlarged recess 9 for a purpose which will hereinafter appear. The guide member 7 is secured as at 10 to the side wall 5, a suitable key hole 11 being provided in the wall 5. 70 One circuit terminal is designated 12 and has connected thereto one of the conductors 13 leading from one side of the external electric circuit. The binding post or terminal 12 carries a resilient arm 14, said arm 75 14 having its free extremity provided with an offset portion 15 and a U-shaped portion 16 for a purpose which will hereinafter appear, said portion 15 being disposed adjacent the guide member 7. The other circuit terminal 80 is designated 17 and carries an angle bar 18, said angle bar 18 having a laterally extending portion 19 for a purpose which will hereinafter appear. As shown to advantage in Fig. 2, the circuit terminals 12 85 and 17 extend radially inward from the curved wall 4 of the housing 1.

I provide a circuit closing arm designated 20, said arm being pivoted at 21 in a bracket 22 mounted upon and insulated from 90 the wall 6 of the housing. The arm 20 is provided with an offset portion 23 adjacent one extremity 24 thereof, said extremity 24 extending adjacent the portion 19 of the angle bar 18. The opposite extremity of 95 the arm 20 extends transversely of and to a point adjacent one extremity of the guide 7, said arm being provided, at a point concentric with the axis of the guide 7, with a depression 25. A recess 26 is provided in 100 the wall 6 of the housing and an expansion spring 27 of any desired type is receivable in said recess and bears upon said arm 20 to maintain the same in the position shown in Fig. 5. A suitable stop comprising a lug 28 is provided on the bracket 22 to a distance to which the arm 20 may be moved by the spring 27.

I provide a suitable circuit closing member which in the present instance includes a 110

key 29 having a shank 30 and a lateral extension 31 similar to the ordinary ward of a key for engagement with the U-shaped portion 16 of the resilient arm 14 in a manner which will hereinafter appear.

It will be noted that, by virtue of the peculiar relative disposition of the arm 20, the guide 7 and the terminal 14, the key 29 may be utilized to actuate the arm 20 and engage at the same time the free extremity of the resilient arm 14. As shown in Fig. 3, the device is in open circuit position. In order to close the circuit, the key is inserted through the hole 11, the shank 30 thereof being received in the guide 7, and the ward 31 of said key extending laterally through the slot 8 in the guide. The key is forced inwardly until the free extremity of the shank 30 engages the socket or depression 25 on the arm 20. This will cause the arm 20 to rock on its pivot 21 causing the extremity 24 of said arm to engage the lateral portion 19 of the bar 18. In this position the ward of the key will be in a position to register with the lateral recess 9 which communicates with the slot 8 in the guide 7. By turning the key a short distance, the ward 31 may be swung into engagement with the U-shaped portion 16 of the resilient arm 14. The key is turned until the ward snaps into the U-shaped portion of the arm, whereupon it will remain in said U-shaped portion until a reverse movement is directed on said key. This will cause the circuit to be closed through the resilient arm 14 to the ward 31 of the key, through the shank of the key to the arm 20, and thence to the other binding post or terminal 17 through the bar 18.

It will be seen that the key both serves to lock the device in closed circuit position and as a conducting path for the electric current. Of course, the shape of the key need not be as shown, since various shapes may be resorted to in actual practice to prevent duplicating said key.

From the above description, taken in connection with the accompanying drawings, it is thought that a clear and comprehensive understanding of the construction, operation, and advantages of my invention may be readily gathered, and, while I have shown and described the same as possessing a peculiar construction, it is to be understood that changes may be made in the details thereof which do not depart from the spirit and scope of the invention as claimed.

What is claimed is:

1. The combination of a guide tube with a slot and a recess communicating therewith, a circuit closing contact pivoted at the end of the guide tube said contact having a depression, a locking contact beside the guide tube with an offset forming a ward lock near the communicating recess, a

key having a shank entering the tube and engaging the depression to move the pivoted circuit closer, a ward on the shank entering the slot and adapted to be moved into the recess to engage the ward lock and simultaneously close and lock the contacts, and means for normally urging the pivoted contact against the shank of the key.

2. The combination of a guide tube with a slot and a recess communicating therewith, a circuit closing contact yieldably supported at the end of the tube, a locking contact beside the guide tube and nearer said recess, a key having a shank entering the tube and engaging the said circuit closing contact for moving the same, a ward on the shank entering the slot and adapted to be moved into the recess to engage the locking contact for closing a circuit.

3. The combination of a locking contact, a circuit closing contact, a key comprising a shank having a ward, means for guiding said shank into engagement with said circuit closing contact and said key being adapted to move into engagement with said locking contact for closing a circuit.

4. The combination of a guide tube with a slot and a recess communicating therewith, a circuit closing contact pivoted at the end of a guide tube, said contact having a depression, means for normally urging said pivoted contact in one direction, a locking contact beside the guide tube with an offset forming a ward lock near said recess, a key having a shank entering the tube and engaging with the depression to move the circuit closing contact, a ward on the shank entering the slot and adapted to be moved into the recess to engage the ward lock and simultaneously close and lock the contacts, and a contact bracket secured in the path of movement of said circuit closing contact.

5. The combination of a guide tube with a slot and a recess communicating therewith, a circuit closing contact yieldably supported at the end of the guide tube, said contact having a depression, a locking contact beside the guide tube and adjacent said recess, a key having a shank entering the tube and engaging the depression to move said circuit closing contact, a ward on the shank entering the slot and adapted to be moved into engagement with said locking contact for moving the same.

6. The combination of a guide tube with a slot and a recess communicating therewith, a yieldably supported circuit closing contact at the end of the guide tube, a locking contact beside the guide tube with an offset forming a ward lock adjacent the recess, a key having a shank entering the tube and engaging said circuit closing contact for moving the same, a ward on the shank entering the slot and adapted to be

moved into the recess to engage the ward lock and simultaneously close and lock the contact.

7. The combination of a guide tube with
5 a slot and recess communicating therewith, a plate having a bracket and a socket, a circuit closing contact pivotally mounted upon said bracket adjacent the end of the guide tube, said contact having a depression,
10 a locking contact beside the guide tube with an offset forming a ward lock near the recess, a spring carried within said pocket and bearing upon said circuit closing contact adjacent said depression, a key having a
15 shank entering the tube and engaging the depression to move the circuit closing contact, a ward on the shank entering the slot and adapted to be moved into the recess to

engage the ward lock and move said locking contact for closing a circuit. 20

8. The combination of a locking contact, a circuit closing contact, a tube extending toward said circuit closing contact, a key comprising a shank having a ward, said tube being adapted to guide said shank into engagement with said circuit closing contact and said key being adapted to move into engagement with said locking contact for closing a circuit. 25

In testimony whereof I affix my signature 30
in presence of two witnesses.

LIONEL F. BARNES.
